UNITED STATES PATENT OFFICE.

ADAM FISCHER, OF CHICAGO, ILLINOIS, ASSIGNEE TO GUARANTY IRON & STEEL CO.,
OF CHICAGO, ILLINOIS, A CORPORATION OF ILLINOIS.

STAIR CONSTRUCTION.

Application filed June 26, 1922. Serial No. 571,008.

To all whom it may concern:

Be it known that I, ADAM FISCHER, a citizen of the United States of America, and a resident of Chicago, county of Cook and State of Illinois, have invented a new and useful Improvement in Stair Construction, of which the following is a specification.

The main objects of this invention are to provide an improved stair construction wherein the steps comprise metal forms assembled on a supporting structure and have wear-resisting treads made from a plastic substance poured into a step form and allowed to harden; to provide an improved 10 stair construction of this kind which permits the use of sheet metal stampings for the step forms; to provide an improved construction and arrangement of said sheet metal stampings; to provide an improved 15 construction and arrangement of a common central support and an improved construction of the step forms whereby said step forms may be assembled on said support in a spiral relation for forming a spiral stair- 20 way; to provide improved means for rigidly securing the steps to said central support; to provide an improved stair construction of 25 this kind which can be manufactured in sections and shipped in knock-down form, the 30 sections being so designed and shaped that the assembling thereof to form a stair is simple and easy; and to provide such a stair construction wherein the replacement of worn or injured steps is convenient and 35 economical.

An illustrative embodiment of this invention is shown in the accompanying drawings, in which—

Figure 1 is a plan of a spiral stairway 40 constructed in accordance with this invention.

Fig. 2 is a side elevation of a portion of the same.

Fig. 3 is an enlarged plan of an improved 45 triangular shaped step adapted for use in the formation of a spiral stairway.

Fig. 4 is a front elevation of one step, and a sectional elevation of another of the type shown in Fig. 3.

Fig. 5 is a sectional detail taken on the line 5—5 of Fig. 3.

Fig. 6 is a fragmentary detail view of the arrangement shown in Fig. 4, the view being taken on the plane of the line 6—6 of said 55 figure.

A stair constructed in accordance with this invention involves the use of a pair of metal stampings shaped so that when assembled to form a step section they provide a horizontally disposed mold into which concrete is adapted to be poured in order to form a tread, and provide a riser in the form of a transversely disposed reinforcing web, each pair of the stampings having a rod secured thereto, by which the step section is secured to a suitable support.

In the specific embodiment herein shown the step sections are constructed so as to be used in the formation of a spiral stairway. Each step section comprises a pair of metal stampings 1 and 2, and is secured to a common central support 3 by means of a rod 4, and each step section is the more rigidly held in place by brackets 5 and rail supports 6.

The metal stampings 1 and 2 might be variously shaped, but in the particular form herein illustrated they are substantially triangular shape. The stamping 1 has flanges 7 and 8 formed along the edges thereof and extending in opposite directions. The stamping 2 has a transversely disposed flange 9 formed along one edge thereof and intermediate its ends is offset obliquely as at 10 so as to provide a laterally disposed flange 11 above the oblique offset 10, the upper edge of which flange is turned over so as to provide a transversely disposed flange or ledge 12. These two stampings are assembled with the flange 8 of the stamping 1 located intermediate the outside edges of the stamping 2, and with the base of the stamping 2 located adjacent to the apex of the stamping 1. These two stampings when thus assembled provide a step mold into which concrete or other suitable cementitious substance is to be poured so as to furnish a wear-resisting tread 13. The ends of the mold are closed by the support 3 and a plate 14, the latter of which is secured to the ends of the stampings by means of the angle bar 14A (see Fig. 4). The stamping 2 below the oblique offset 10 constitutes the riser for the step and also serves as a reinforcing web for the same.

The support 3 as herein shown is in the form of a pipe, the ends of which are secured by suitable plates or brackets (not shown) to the floor construction which the stair connects. At suitably spaced intervals, 105

110

and in the desired angular arrangement holes 15 are formed in the pipe 3, through which the step supporting rods 4 extend.

The rod 4 extends lengthwise of the step, 5 and is secured to the flange 11 by one or more angle clips 16. The length of the rod is such that its inner end protrudes beyond the step a sufficient distance to extend through the pipe 3, and its outer end beyond 10 the plate 14. Nuts 17 and 18 are secured on the respective ends of the rod, which are adapted to be drawn up so as to firmly clamp the step to the pipe 3. The rod being buried in the concrete tread 13, further rigidly secures the rod and step together.

When assembled on the post or support 3 the steps are further braced and secured in their relative positions by the plates or brackets 5 and the rail supporting posts 6. 20 Each of the plates 5 is in the form of a strip of metal, the lower end of which is secured to the inner end of a flange 7 of one step by means of a suitable bolt and nut 19, and at intervals along the length of the brace 25 above said step is secured by rivets 20, or other means to the stamping 2 adjacent to the base thereof. The post support 6 is in the form of a bar of rectangular cross-section secured at its lower end to the plate 14 30 of one step, and to the forward projecting part of the plate 14 and the step above, as is most clearly indicated in Fig. 6. These posts 6 are of such a length that the upper ends thereof are disposed so that a pipe or 35 rod 21 is rigidly secured to the tops thereof and provides a hand rail for one ascending or descending the stairway.

The advantage of a stair construction of this kind is that the step forms or sections 40 can be made up of sheet metal stampings, and the other parts suitably cut and shaped so that the stair can be shipped in knock-down form, and after arrival at its destination may be quickly and easily set up. Being 45 stampings the step parts are less expensive to manufacture than castings and are in many respects stronger and more durable. After the step forms have had the concrete 50 poured therein and allowed to harden, a very substantial and rigid stair construction is provided. In the event that one of the steps becomes injured or for some other reason 55 needs replacing it can be quickly and conveniently accomplished.

55 Although but one specific embodiment of this invention has been herein shown and described, it will be understood that numerous details of the construction shown may be altered or omitted without departing 60 from the spirit of this invention as defined by the following claims.

I claim:

1. A stair construction comprising a step section made up of two metal stampings secured together to provide a horizontal part

and a transverse reinforcing web, and upstanding perimetral flanges formed along one radial edge and the end of said horizontal part, said horizontal part being secured along its other radial edge to said transverse web below the top edge thereof whereby a portion of said web coacts with said perimetral flanges to form a mold for a cementitious tread.

2. A stair construction comprising a step 75 section made up of two metal stampings each of substantially triangular form secured together with the edge of one stamping located intermediate the edges of the other so as to provide a horizontal part and a transverse reinforcing web, the base of the other stamping being located adjacent the apex of said one stamping, perimetral flanges on said horizontal part coacting with the upper portion of said transverse part to provide a 80 mold for a concrete tread.

3. A stair construction comprising a step section made up of two metal stampings of substantially triangular form, one of said stampings having flanges formed along the 90 edges thereof, the other stamping having a longitudinal offset intermediate its edges whereby the portions thereof are disposed in spaced substantially parallel planes, said stampings being secured together with the radial edge of said one stamping extending longitudinally of the other adjacent to said offset, and with the flange along the outer radial edge extending upwardly and coacting with the upper portion of said other stamping to provide a mold for concrete.

4. A stair construction comprising a step section made up of two metal stampings of substantially triangular form, one of said stampings having flanges formed along the 105 edges thereof, the other stamping having a longitudinal offset intermediate its edges whereby the portions thereof are disposed in spaced substantially parallel planes, said other stamping having 110 an inwardly disposed transverse flange formed along the upper radial edge thereof, said stampings being secured together with the radial edge of said one stamping extending longitudinally of the other adjacent to 115 said offset, and with the flange along the outer radial edge extending upwardly and coacting with the upper portion of said other stamping to provide a mold for concrete.

5. A stair construction comprising a step 120 section made up of two metal stampings secured together to provide a horizontal part and a transverse reinforcing web, upstanding perimetral flanges formed along one radial edge and the end of said horizontal part, said horizontal part being secured along its other radial edge to said transverse web below the top edge thereof whereby a portion of said web coacts with said perimetral flanges to form a mold for a cementitious tread, and

a rod rigidly secured to said transverse reinforcing web above said horizontal part, said rod having the end thereof projecting beyond said stampings to permit said step section to be secured to a support.

6. A stair construction comprising a step section made up of two metal stampings of substantially triangular form, one of said stampings having flanges formed along the edges thereof, the other stamping having a longitudinal offset intermediate its edges whereby the portions thereof are disposed in spaced substantially parallel planes, said stampings being secured together with the radial edge of said one stamping extending

longitudinally of the other adjacent to said offset, and with the flange along the outer radial edge extending upwardly and coacting with the upper portion of said other stamping to provide a mold for concrete, 20 and a rod rigidly secured to the inside face of the upper offset portion of said other stamping, said rod having the end thereof project beyond said stampings so as to permit said step section to be secured to a 25 support.

Signed at Chicago this 24th day of June, 1922.

ADAM FISCHER.
